United States Patent Office

Des. 201,631
Patented July 13, 1965

201,631

TRAY OR THE LIKE

Esther M. Quaritere, 67 N. Howells Point Road,
Bellport, N.Y.

Filed Dec. 16, 1964, Ser. No. 83,059

Term of patent 14 years

(Cl. D44—10)

FIG. 1

FIG. 2

FIG. 3

FIG. 1 is a top plan view of a tray showing my new design.

FIG. 2 is a side elevational view; and
FIG. 3 is an end elevational view.

I claim:

The ornamental design for a tray or the like, substantially as shown.
